(57) **CLAIM**

The ornamental design for a mop plate, as shown and described.

DESCRIPTION

The plate illustrated in the following drawings is useful for instance as a sponge backing plate on a cleaning implement of the type commercially used as a “butterfly sponge mop.”

FIG. 1 is perspective view of the mop plate;

FIG. 2 is a top plan view of the mop plate;

FIG. 3 is a first side elevational view of the mop plate;

FIG. 4 is a second side elevational view of the mop plate;

FIG. 5 is a front elevational view of the mop plate;

FIG. 6 is a rear elevational view of the mop plate; and,

FIG. 7 is a bottom plan view of the mop plate.

1 Claim, 3 Drawing Sheets

FIG. 1

FIG. 4

FIG. 5

FIG. 2

FIG. 6

FIG. 3

FIG. 7

UNITED STATES PATENT AND TRADEMARK OFFICE
CERTIFICATE OF CORRECTION

PATENT NO. : Des. 508,759 S
DATED : August 23, 2005
INVENTOR(S) : Boyer et al.

Page 1 of 1

It is certified that error appears in the above-identified patent and that said Letters Patent is hereby corrected as shown below:

Title page.

Item [57], **DESCRIPTION**,
Line 3, "commercercially" should be -- commercially --.
